(57) **CLAIM**

The ornamental design for a light emitting device, as shown and described.

DESCRIPTION

FIG. 1 is a perspective view of a light emitting device showing our design;

FIG. 2 is a top view thereof;

FIG. 3 is a side view thereof, the opposing and adjacent sides being mirror images of that shown;

FIG. 4 is a bottom view thereof;

FIG. 5 is a perspective view of a second embodiment of a light emitting device showing our design;

FIG. 6 is a top view thereof;

FIG. 7 a side view thereof, the opposing and adjacent sides being mirror images of that shown; and,

FIG. 8 is a bottom view thereof.

The dashed broken lines are for illustrative purpose only and form no part of the claimed design. The dot-dash-dot broken lines represent boundaries of the claimed design and form no part of the claimed design.
